UNITED STATES PATENT OFFICE.

SAMUEL C. BLOOM, OF CHICAGO, ILLINOIS.

REFRIGERATING COIL.

Application filed June 2, 1927. Serial No. 196,093.

This invention relates to improvements in refrigerating coils and more especially to such a coil of the boiler type with headers joined by a plurality of conducting or circu-
5 lating pipes.

My improved refrigerating coil is adapted for use in connection with any refrigerating apparatus, such coil constituting the expansion coil or chamber in which the refrigerant 10 expands and thus absorbs heat. The principal parts of ordinary refrigerating apparatus such as the compressor, condenser, and the like, are old in the art and their manner of use is well known; and consequently it is 15 unnecessary to show the same here. This invention relates more particularly to the refrigerating coil or expansion chamber adapted for use in any ordinary refrigerating system and consequently such refrigerating coil 20 or expansion chamber only will be shown and described in this application.

One of the features of my invention is the provision of such a coil that will insure a uniform and even distribution of the refrigerant 25 through the parts thereof, thus giving all parts of the coil a substantially uniform temperature.

The coil is so constructed that practically only dry gas is withdrawn from the same by 30 the pump. Even though refrigerant in its liquid phase, is present at high levels in the coil, the possibility of withdrawal of the same from the coil by the pump is reduced to a minimum.

My improved coil is, also, so constructed that it may be easily cleaned, drained and emptied of foreign substances.

Other features and advantages of my invention will appear more fully as I proceed 40 with my specification.

In that form of invention embodying the features of my invention shown in the accompanying drawings, Fig. 1 is a view in perspective of my improved coil, Fig. 2 is a view 45 taken as indicated by line 2 of Fig. 1 and Fig. 3 is a view taken as indicated by line 3 of Fig. 1.

As shown in the drawings, the coil comprises an upper suction header 10 and a lower 50 liquid header 11 joined by a row of outwardly bowed connecting or circulating pipes 12, 12 on each side. The pipes on one side are preferably staggered in respect to those on the other. 13 indicates a liquid feed pipe com-
55 ing from the compressor (not shown); and

14 indicates a dry pipe leading from the coil to the compressor (not shown).

The liquid feed pipe 13 enters the liquid header 11 at the bottom in the center and projects upwardly a short distance inside. 60 Its upper end is threaded into a liquid distributing header 15 centrally arranged in the header 11 and extending substantially the entire length of the same. The distributing header 15 is preferably supported in position by a lug 16 welded to it near each end. The liquid distributing header 15 is provided with a plurality of outlets 17 distributed throughout its length. These outlets should be sufficient in number and size and so distributed as to give a substantially uniform-
65 issuance or distribution of the refrigerant throughout the length of the header 11. These outlets are preferably arranged at the sides of the header 15, and one or more of 70 such outlets may be provided at the bottom as shown.

The liquid feed pipe 13 is, also, provided near its end, inside of the header 11, just below the distributing header 15 with four oil 80 drain openings 18, as shown. The purpose of these openings is to permit entire draining and emptying of the coil when desired. It will be seen that these openings are sub-
85 stantially flush with the bottom of the header 11; and, therefore, if desired, the coil may be entirely drained or emptied through these openings by withdrawing the contents through the pipe 13. If desired this may be accomplished by reversing the action of the 90 pump. Such suction through the pipe 13 will serve to empty the coil of any accumulation of oil or any other foreign matter that it may contain.

A dry pipe 14 projects inside of the upper 95 header 10 throughout substantially the entire length of the same as indicated by 14^a and is arranged very close to the top thereof. Its extreme end is preferably supported by a lug 19 formed on the end of the header 10. 100 The top of the dry pipe 14^a is provided with suction holes or openings 20, 20 which lie close to the upper wall of the header 10, as shown. By means of this construction, like-
lihood of liquid refrigerant entering the holes 105 20 is reduced to a minimum. Since these suction holes are arranged at the very highest level in the coil, it will be seen that only the driest gas is permitted to enter the same.

While I have shown and described but a 110

single embodiment of my invention, it is to be understood that it is capable of many modifications. Changes, therefore, in the construction and arrangement may be made 5 without departing from the spirit and scope of the invention as disclosed in the appended claims, in which it is my intention to claim all novelty inherent in my invention as broadly as possible in view of the prior art.

10 What I claim as new, and desire to secure by Letters Patent, is:

1. A refrigerating coil comprising; an upper suction header; a lower liquid header; a plurality of circulating pipes joining said 15 headers; a dry pipe connected to the suction header; a liquid distributing header in the liquid header provided with a plurality of outlets; and a liquid feed pipe connected to said liquid distributing header.

20 2. A refrigerating coil comprising; an upper suction header; a lower liquid header; a plurality of circulating pipes joining said headers; a dry pipe connected to the suction header; a liquid distributing header centrally 25 arranged in the liquid header; and a liquid feed pipe connected to said liquid distributing header.

3. A refrigerating coil comprising; an upper suction header; a lower liquid header; a 30 plurality of circulating pipes joining said headers; a dry pipe connected to the suction header; a liquid distributing header in the liquid header extending substantially the entire length of the same; and a liquid feed 35 pipe connected to said liquid distributing header.

4. A refrigerating coil comprising; an upper suction header; a lower liquid header; a plurality of circulating pipes joining said 40 headers; a dry pipe connected to the suction header; a liquid distributing header centrally arranged in the liquid header, extending substantially the entire length of the same, and provided with a plurality of outlets; 45 and a liquid feed pipe connected to said liquid distributing header.

5. A refrigerating coil comprising; an upper suction header; a lower liquid header; a plurality of circulating pipes joining said 50 headers; a dry pipe connected to the suction header; a liquid distributing header in the

liquid header provided with a plurality of outlets; and a liquid feed pipe entering the liquid header and having its end connected to the liquid distributing header, said liquid feed pipe being provided with a drain opening 55 inside of the liquid header.

6. A refrigerating coil comprising; an upper suction header; a lower liquid header; a plurality of circulating pipes joining said 60 headers; a dry pipe connected to the suction header; a liquid distributing header in the liquid header provided with a plurality of outlets; and a liquid feed pipe entering the liquid header and having its end connected to the liquid distributing header, said liquid feed pipe being provided with a drain opening 65 inside of the liquid header, and substantially flush with the bottom thereof.

7. A refrigerating coil comprising; an upper suction header; a lower liquid header; a plurality of circulating pipes joining said 70 headers; a liquid feed pipe connected to the liquid header; and a dry pipe connected to the suction header, the end of said dry pipe 75 extending into said suction header, and lying near the upper wall thereof, said end of the dry pipe lying in the suction header being provided with suction openings in its upper wall.

8. A refrigerating coil comprising; an upper suction header; a lower liquid header; a plurality of circulating pipes joining said 80 headers; a liquid feed pipe connected to the liquid header; and a dry pipe connected to the suction header, the end of said dry pipe 85 extending into said suction header through substantially the entire length of the same.

9. A refrigerating coil comprising; an upper suction header; a lower liquid header; a 90 plurality of circulating pipes joining said headers; a liquid feed pipe connected to the liquid header; and a dry pipe connected to the suction header, the end of said dry pipe extending into said suction header through 95 substantially the entire length of the same, and being provided with openings throughout the entire length of said end.

In testimony whereof, I have hereunto set my hand this 31st day of May, A. D. 1927.

SAMUEL C. BLOOM.
